GRASS CLIPPER

Douglas W. Anderson, deceased, by Elizabeth A. Anderson, administratrix, Palatine, Ill., assignor to Burgess Vibrocrafter, Inc., Grayslake, Ill.

Filed Jan. 3, 1972, Ser. No. 215,286

Term of patent 14 years

Int. Cl. D8—03

U.S. Cl. D8—8

FIG. 1 is a perspective view including the front, top and right side of a grass clipper showing my new design, FIG. 2 is a top plan view thereof, and

FIGS. 3, 4 and 5 are elevational views showing respectively, the left side, front and back of the grass clipper.

I claim:

The ornamental design for a grass clipper, substantially as shown.
